UNITED STATES PATENT OFFICE.

JAMES A. WOTTON, OF ATLANTA, GEORGIA.

ANNUNCIATOR.

No. 813,931.

Specification of Letters Patent.

Patented Feb. 27, 1906.

Application filed May 16, 1904. Serial No. 208,226.

To all whom it may concern:

Be it known that I, JAMES A. WOTTON, a citizen of the United States, residing at Atlanta, in the county of Fulton and State of Georgia, have invented certain new and useful Improvements in Annunciators; and I do hereby declare the following to be a full, clear, and exact description of the invention, such as will enable others skilled in the art to 10 which it appertains to make and use the same.

This invention relates to improvements in electrically-operated indicating mechanism, and particularly to that class of instruments 15 known as "annunciators."

While the invention is adapted for use wherever indicating devices are useful, it is especially well adapted for use in connection with telephone-exchanges where annunciators or drops are required.

The invention consists in an annunciator comprising a rotating indicator, an armature carrying the same, a magnet having its poles projecting adjacent to the said armature, and 25 means for connecting the magnet with certain electric circuits.

It also consists in an annunciator comprising a rocking indicator, an armature secured thereto and carrying the same, a magnet 30 movably mounted adjacent to the armature, the magnet being easily replaceable at any time, while the indicator and armature can also be removed without affecting the magnet, and means for electrically connecting the 35 magnet in a telephone-circuit.

It also consists in certain other novel constructions, combinations, and arrangements of parts, as will be hereinafter fully described and claimed.

40 In the accompanying drawings, Figure 1 is a front elevation of a portion of a telephone-annunciator. Fig. 2 is a longitudinal central section through one member of the annunciator. Fig. 3 is a detail sectional view through the poles of the annunciator-magnet and the pivot-pin carrying the armature thereof, the armature and indicating-disk carried thereby being shown in rear elevation. Fig. 4 is a front elevation of the plate to which the 45 magnet of the annunciator is secured, the poles thereof being shown as projecting through the plate, while the indicating-disk and its armature, together with the front plate, are removed. Fig. 5 is a view in elevation of the 50 indicator or disk provided with light and

dark surfaces for quickly attracting the attention of the operator when in use.

The present invention is useful in all instances where indicating means are desired and is useful in connection with annunciators 50 of all sorts—such as those employed in hotels, houses, railway-carriages, or the like—but is especially useful in connection with a telephone system, and in the accompanying drawings the mechanism has been illustrated 55 as adapted for use in a telephone-exchange.

The object of the invention is the production of an annunciator or drop for a telephone or other purpose in which the indicating drop or disk, together with its armature, can be 60 easily reached for repair or adjustment without disturbing the actuating-magnet or its electrical connections.

The invention also has for a further object the arranging of the parts so that the magnet 75 of the annunciator can be easily removed and repaired or replaced at any time without disturbing the annunciator or indicator or its armature. This is frequently necessary in telephone-exchanges, since the magnets are 80 frequently disturbed, injured, or destroyed by the action of lightning or other heavy electrical currents.

Referring now to the accompanying illustration, the indicator and its armature, together with the actuating-magnet, are supported by a plate 1. Projecting from said plate is a pin or stud 2, upon a reduced portion of which is pivotally mounted an armature 3. The armature is held upon said reduced portion by means of a nut or threaded washer 4, which is screwed upon the end of the stud. By removing the nut 4 the armature 3 can be taken from its stud at any time. Upon the front face of the armature is secured an 95 indicator 5, which is preferably a thin plate or disk having its surface marked with distinguishing colors, as shown in Fig. 5. The portions 6 are generally made black, while the portions 7 are made white, so as to make a 100 decided contrast with the same. The armature 3 is approximately S shape in elevation, as clearly shown in Fig. 3, the said armature having a straight body portion extending beyond the pivot-stud on each side and is provided at its outer ends with laterally-projecting tapering curved portions 8. The armature is preferably weighted, so as to normally assume the position shown in Fig. 3, with the small or reduced ends of the tapering por- 110

tions 8 adjacent to the poles of the magnet. The weight 9 may be applied to the armature in any suitable manner or may, as shown in the drawings, be secured to the disk or indicator 5. The weight in this instance consists in a small segmental block fastened to the inner face of the indicator 5 in such a position that when the poles of the magnet are demagnetized the action of gravity will bring the parts into the position shown in Fig. 3. One or more stops or pins 10, projecting from the face of the plate 1, limit the movement of the armature, so that the ends of the tapering portions 8 are sufficiently near the poles of the magnet to be attracted when the magnet is energized.

Upon the front of the plate 1 an outer covering-plate 11 is secured, the said covering or face plate being formed with apertures 12, which register with the divisions or indications placed upon the disk or indicator 5. These apertures 12 are so shaped that when the indicator is held in its normal position by the weight 9 the darkened or black portions 6 only will show through the said openings. When the armature is affected by the magnet, as will be hereinafter described, so as to turn the indicator 5, the light or white portions 7 will appear behind the openings 12. The face-plates 11 may be secured to the plate 1 in any desired manner, but are preferably fastened thereto by means of removable screws 13, which pass through spacing-sleeves 14. The face-plate 11 may be removed at any time for adjusting or repairing the indicator or its armature or for removing and replacing the same. In employing the device in an ordinary telephone-exchange a number of indicators are arranged side by side, as shown in Fig. 1, and by providing a separate face-plate for each of the indicators any one of them may be removed for reaching the mechanism upon them without interfering with the adjacent face-plates or indicators.

Upon the rear of the plate 1 is mounted an electromagnet for each indicator. Each magnet is made in an ordinary manner, being provided with cores 15, surrounded by coils 16, wound in any usual or ordinary manner. The ends of the coils are secured to a plate 17 at one end, which plate is removably attached to the main plate 1. The pole ends 18 of the magnet project through the plate 17 and also through apertures 19, formed in the plate 1. The projecting ends of the poles are preferably approximately crescent shape, as shown in Figs. 3 and 4 of the drawings, the inner surfaces of the said poles being formed upon arcs concentric with the periphery of the armature 3. In this manner the curved ends of the armature 3 may be moved quite closely to the inner surfaces of the poles 18, the cores 15 being connected at their outer ends by a plate or bar 20. The windings of

the coils 16 are connected with each other in the usual manner, and conductors or wires 21 and 22 extend from the said coils to such points that they may be connected with the telephone instruments of a telephone system. These coils are usually so connected as to be in circuit with the receivers or transmitters, or both, of the telephone, and when the receiver is removed from its hook, as in making a telephone-call, a circuit will be completed through the magnet, energizing the poles and acting upon the armature 3. As soon as the poles of the magnet are energized they will exert a pull upon the reduced ends 3 of the magnet and will draw the same until the straight body portion of the armature lies across from one pole to the other, thus affording an easy passage for the magnetic flux in its travel from one pole to the other. The strength of the magnet will be sufficient to move the armature 3 against the action of the weight 9. The moving of the armature will of course effect a movement of the disk or indicator 5, and the white or light surfaces 7 appearing through the apertures in the face-plate 11 will attract the attention of the central operator. As soon as the central operator responds and makes the proper connections the magnet will be cut out of circuit and the weight 9 will return the indicator to its normal position. When the magnet turns the armature 3, the white or contrasting surfaces 7 appearing behind the blackened plates 11 will readily attract the eye. It is important that the magnets shall be easily removable from the plate 1 and in such a manner as to not disturb the armature or disk. The magnet and its poles are therefore carried by the plate 17, as above indicated, and this plate is provided with ears or projections 23, through which screws 24 are passed, the said screws engaging threaded apertures in the plate 1. The poles 18 project loosely through the apertures 19 in the plate 1, and when the screws 24 are removed the magnet can be easily taken from its normal position. Any one of the magnets at the rear of the plate 1 can be gotten at from the rear at any time and removed or replaced or repaired with ease.

While I have above described the magnets as so connected that when a current is passed through them they will move the armature and the indicating-disk into position to expose the dark surfaces of the indicator behind the opening 12, yet it will be apparent that the magnets might be so connected as to normally return the indicating-disk, so that the darkened or non-attracting surface of the indicator will appear at the apertures 12, while the weight may be so arranged as to move the indicator to its indicating position when the magnet releases the armature without departing in the least from the spirit of the invention.

The annunciator constructed in accordance with this invention is so formed that any one of the indicators can be easily and quickly reached without disturbing the magnets and also any one of the magnets can be easily reached and removed without disturbing the armatures or indicators. The armatures and indicators are reached from one side of the main plate 1, while the magnets are reached from the other side thereof. Since the magnets are often disabled or crippled from the action of lightning, the ease with which such magnets can be reached and replaced forms a valuable feature of the invention.

It will be understood that I contemplate employing any style or shape of indicator and using the same in connection with house, hotel, or other annunciators, as well as with telephone-drops, as above described, all within the spirit of the invention.

Having thus fully described my invention, what I claim as new, and desire to secure by Letters Patent, is—

1. An annunciator comprising an armature and an indicator carried thereby and a magnet arranged with its axis parallel with the axis of the armature the said magnet having poles projecting from its coils, the said poles having their axes also parallel with the axis of the armature and capable of operating the armature, the said magnet with its poles being removably mounted so that it may be withdrawn without disturbing the armature of the indicator.

2. An annunciator comprising a supporting-plate, an armature removably mounted upon one side thereof, an indicator carried by the said armature and a magnet removably mounted on the opposite side of the plate from the armature, the poles of the magnet extending to points adjacent to the armature, the removal of the magnet being accomplished without disturbing the armature or the indicator.

3. An annunciator mechanism comprising a supporting-casing, an approximately S-shaped armature mounted therein, an indicator secured to the armature and carried thereby, and a magnet secured to the said casing outside thereof the poles of said magnet projecting through the walls of the casing so as to occupy positions adjacent to the periphery of the armature.

4. An annunciator mechanism comprising

a supporting-plate, a stud projecting therefrom, an armature mounted upon the said stud, an indicator carried by the armature, and a magnet mounted upon the plate with its axis approximately at right angles to the plane of the indicator the said magnet being bodily removable therefrom without disturbing the indicator, the poles of said magnet extending to positions adjacent the armature for affecting the same when energized.

5. An annunciator mechanism comprising separable indicating mechanism and actuating mechanism, the indicating mechanism comprising an armature and an indicator carried thereby and a weight mounted upon the indicator tending to hold it normally in one position, the actuating mechanism comprising a magnet arranged adjacent to the armature, but removable therefrom longitudinally, parallel with its axis without disturbing the armature and indicator, the poles of the magnet being capable of actuating the armature against the action of the weight.

6. An annunciator mechanism comprising an inclosing casing, an apertured face-plate secured thereto, an armature mounted in the casing, an indicator carried by the armature immediately to the rear of the face-plate, the surface of the indicator showing through the apertures in the face-plate, a removable magnet mounted outside the casing on one of the walls thereof, the poles thereof projecting through the casing-wall to points adjacent to the said armature for affecting the same.

7. An annunciator mechanism comprising a supporting frame or casing, a removable armature mounted therein, a rocking indicator carried by the said armature, a weight upon the indicator for holding the indicator normally in a given position, stops carried by the frame for engaging the armature and limiting its movement, and a magnet removably mounted upon the outside of the casing, the poles thereof projecting within the casing for moving the indicator against the action of the weight the longitudinal movement of the magnet causing the withdrawal of the poles without disturbing the indicating mechanism.

In testimony whereof I hereunto affix my signature in presence of two witnesses.
